PRESSER FOOT, WORK HOLDER, AND ACTUATING MEANS THEREFOR FOR SEWING MACHINES

Arthur Rosenthal, Grand Rapids, Mich., assignor to Rose Label Machine Company, Grand Rapids, Mich.

Application July 21, 1930, Serial No. 469,469

14 Claims. (Cl. 112—104)

The objects of the invention are:

First, to provide a complete and substantially automatic means for attaching labels or patches or for similar stitching work.

5 Second, to provide an improved gear means in such a structure.

Third, to provide an improved work holder actuating means.

Fourth, to provide such a means that is adjustable for the stitching.

10 Fifth, to provide such a means that is adjustable for the holding of a label.

Sixth, to provide an improved control means for stopping and starting such a structure.

15 Seventh, to provide an improved label presser foot means.

Eighth, to provide improved means for guiding the work to the needle for stitching.

10 Ninth, to provide improved means for feeding the label.

Objects pertaining to details and economies of construction and operation will appear from the description to follow.

A preferred embodiment of my invention is 20 illustrated in the accompanying drawings, in which:

Fig. 1 is a detail perspective view of my improvements applied to a sewing machine, the sewing machine arm and base being illustrated in dotted lines.

25 Fig. 2 is a detail side elevation from the left hand side of the machine, the base being in section and the mechanism below the base being indicated by dotted lines, as are also the sewing machine arm and a part of the head, the view being taken on a line corresponding to line 2—2 of Fig. 3.

30 Fig. 3 is a detail sectional plan view of my improved mechanism in place on a sewing machine, taken on irregular section lines 3—3 of Figs. 2 and 6, the sewing machine arm and head being broken away and partially indicated by dotted lines, the driven pulley and the ratchet drive for the work holder carrier plate being in full lines.

35 Fig. 4 is a much enlarged detail plan view of the work presser foot, the label presser foot being shown at the starting point, its movement being shown by dotted lines, and the presser foot bar being in section.

40 Fig. 5 is a detail diagrammatic plan view to indicate the method of stitching the label.

45 Fig. 6 is a detail cross-sectional view on line corresponding to line 6—6 of Figs. 2, 3 and 7, the parts being shown in full lines.

50 Fig. 7 is a detail plan view of the work holder

actuating plate or means taken on section line 7—7 of Figs. 2 and 6.

Fig. 8 is an enlarged detail sectional view of the control means taken on section line 8—8 of Figs. 3 and 9.

Fig. 9 is an enlarged detail sectional view taken on section line 9—9 of Figs. 3, 6 and 8.

Fig. 10 is an enlarged detail sectional view on line 10—10 of Fig. 6, showing the method of adjusting the throw of the feed actuating means.

Fig. 11 is an enlarged detail sectional elevation view on line 11—11 of Figs. 8 and 9, showing the relation of the cams to the reciprocating links and guides.

Fig. 12 is an enlarged detail sectional elevation view taken on line corresponding to line 12—12 of Figs. 2, 3, 4, 14 and 16.

Fig. 13 is an enlarged detail sectional view on line 13—13 of Figs. 3 and 4, showing details of the thread cutter operating lever mechanism.

Fig. 14 is an enlarged detail sectional elevation view taken on line 14—14 of Figs. 3, 4 and 12, showing details of means for manipulation and feeding of the label.

Fig. 15 is a detail perspective view of the label 25 presser foot detached.

Fig. 16 is an enlarged detail sectional plan view taken on line 16—16 of Figs. 2 and 12, showing details of the upper thread cutter and clamp.

Fig. 17 is an enlarged detail sectional elevation 30 view of the cam control means for the thread holder and cut-off, the cutter plate being broken away to show details of construction and operation.

The parts will be identified by their numerals 35 of reference which are the same in all the views.

1 is the sewing machine base, 2 is the sewing machine arm, and 3 is the sewing machine head.

4 is the work holder plate which is movable over 40 the base or bed of the sewing machine in all directions to carry the work. The plate is apertured at the center.

Above the work holder plate is superposed the work presser shoe 5 within which is disposed the label presser foot 6. The work holder is 45 carried on the arm 7 of the work holder carrier 8. The work holder carrier 8 reciprocates back and forth on the slide 9 and the slide 9 reciprocates laterally in adjustable ways 10 carried on the sewing machine base 1.

The work holder carrier 8 is provided with 50 racks 81, 82 disposed at right angles to each other and having elongated teeth which are slidable back and forth on their driving pinion segments.

55

Rack 81 is engaged by driving pinion segment 11 which is secured to rocking sleeve 12 by set screw 111. This sleeve is journaled in bearing 13 supported on plate 14 above the work holder carrier 8. When the pinion segment 11 is rocked to and from it moves the work holder carrier forward and back and the work holder is free to slide to the right and left owing to the elongated teeth of the rack 81.

10 The rack 82 is actuated by pinion segment 15 which is carried on shaft 16 supported in bearings 17 on the plate 14 above the work holder carrier 8. The shaft 16 is provided with beveled gear 161 which is driven from shaft 18 carrying bevel driving gear 181. The shaft 19 is journaled within the sleeve 12 and is capable of rocking motion therein so that both the sleeve 12 and shaft 18 are rockshafts.

15 It will thus be seen that by the actuation of the gear segments 11 and 15 successively, the work holder carrier 8 may be given a rectangular movement. By operating the same simultaneously in different relations, diagonal, circular or any desired form may be given to the path of movement of the work holder carrier 8 and a corresponding movement, of course, given to the work plate 4 that is carried thereby. Any form of label or patch can thus be stitched, or the stitching may be in any design, as a written 20 name or a trademark.

25 The work is delivered to the sewing machine at the proper rate and proper time for stitching and the movement should be step by step to permit the proper action of the needle, and this should be done whether the movement is in straight lines, on the diagonal, or in curved or circular 30 movement.

35 I therefore provide for a step by step movement by a ratchet means which actuates cam means for effecting the movement of the work holder. The ratchet action, of course, being in one direction, leaves the work at rest at the proper interval for stitching.

40 19 is a double faced cam wheel supported on stub axle 20. This cam wheel is provided with ratchet teeth 191 on its periphery and also with cam groove 192 on the outer face and cam groove 193 on its inner face. The cam grooves are for actuating the segments.

45 50 The outer cam groove 192 actuates and rocks the segment 15. This is done by means of pitman 21 provided with a cam roller 211 which is acted upon by the cam groove. The cam groove 192 is provided with rests so that during a part of its movement the pitman is idle, and this is held in this position for rectangular movement of the work, while the opposite cam groove 193 is acting. The rests on the cam grooves 192 and 193 alternate. The actuating parts drive the work holder 55 alternately in opposite directions, thus in the machine here shown stitching a rectangular label.

60 The pitman 21 is connected to rocker arm 22 which is secured to the shaft 18 and rocks the same as the pitman is reciprocated. The pivotal connection of the pitman 21 to the rocker arm 22 is adjustable by set-screw 221 so that the extent of the throw may be regulated in that way, which enables the adjustment to different-sized labels as well as proper adjustment and location 65 of the stitching within the margin of the label.

70 The pitman 21 is guided in its reciprocation by the guide 23 which is provided with a suitable groove and the guiding roller 231 which compels the pitman to move in a proper path in its reciprocation by the cam.

75 Cam groove 193 on the opposite side of cam wheel 19 in like manner controls the segment 11. This is done by precisely similar lever and cam connections to that for cam groove 192.

80 Pitman 24 with roller 241 engaging cam 193 is connected to a rocker arm 25 on the sleeve 12, the pivotal connection of the pitman being adjustable by thumb-screw 251.

85 It will thus be seen that as the cam wheel is gradually rotated it will gradually feed the label 10 in a predetermined rectangular position.

90 The ratchet teeth 191 of the cam wheel are acted upon by a multiple pawl 26 which, because of the multiple engaging of the teeth, insures very fine adjustment and very fine action. This 15 pawl is carried by rockshaft 261 having arm 262 disposed on swinging arm 263. This pawl is actuated by pitman 21 which is driven from wrist pin 271 on adjustable head 272 driven by the 20 stitch feeding drive shaft 273, see Fig. 6. As the parts are rotated the pawl will feed the ratchet wheel a predetermined amount step by step at the right rate for stitching. The wrist pin 271 is adjustable back and forth from the center, to regulate the throw, by the opposed set-screws 274 and 275, and means illustrated particularly in Fig. 10.

95 A multiple detent pawl 28, see Fig. 9, is provided to cooperate with the feed pawls. This is operated from rockshaft 281 having arm 282. 30 This multiple pawl is controlled from rockshaft 29. This rockshaft carries a cam finger 291 which actuates the slide 292 by engaging a pin 293 thereon. This slide is provided with actuating pins 294, 295 which act upon levers 262 and 35 282 to release the pawls 26 and the detents 28 for lifting them out of engagement with the teeth 191 of the ratchet wheel. A return spring 298 is provided for the slide 292.

100 This means is actuated at the end of each operation to permit the back-setting of the cam wheel 19 so that the stitching at the beginning and at the end of affixing each label may overlap. This is done in connection with the stop means. This is controlled by bar 33 hereinafter described. 45

105 I provide my improved machine with the usual standard construction of stop motion such as appears on the Union button sewer. I therefore do not detail the same further than to state that the parts are actuated by rockshaft 30 which 50 is held in latched position by pawl 31, which pawl is tripped into the position indicated in Fig. 8 to release the machine for stopping.

110 This latch is operated by the plunger 32 which is tripped by lug 199 on the cam wheel 19, see 55 Figs. 8 and 9. When the machine is thus stopped the presser feet are raised by depressing the vertical actuating bar 33.

115 The rockshaft 29 is supported in bearings 299 and actuated by link 331 on arm 291 on the said 60 rockshaft 29. When this rockshaft, as before described, has swung to the position for disengaging the pawls, the pin 291' on the arm 291 engages stop 195 on wheel 19, (see Fig. 9) which, because the actuating and detent pawls are 65 disengaged, can be set back several notches which sets the same correspondingly back of its normal starting position so that the first movement of the feed overlaps the final path of the needle forming an overlapping of the stitching at that 70 point.

120 Of course, in order to do stitching and work the fabric of the garment 34 should be inserted on the work plate under the work presser foot 5, and in order to do this it is necessary to provide the 75

presser foot 5 with means for elevating it, which here consists of the lever 35 pivoted at 351 to the arm of the sewing machine, the same being connected by curved link 352 to actuate the rockshaft 5 36 by connection to the rockshaft arm 361. This rockshaft arm 361 has a suitable connection 362 for elevating the work presser foot by rocking shaft 36 and its lug 363, see dotted lines in Fig. 3.

The work presser foot is held yieldingly down 10 by the springs 363 reacting against the shelf 3' carried by the sewing machine head 3. It is clear that when the work presser foot is raised the fabric of the garment may be inserted therebeneath for clamping upon the work plate 4. This 15 method of raising and lowering the work presser foot is common in this class of machines and I have therefore not detailed it at great length. The work presser foot is provided with side arms which are spaced to correspond to the aperture in the 20 work plate 4 therebeneath.

The work presser foot 5 is, as stated, made up of adjustable sides 51, 52 which are adjustably secured in place by set screws 53, 54 on cross bar 55 at the rear. Bars 51 and 52 are attached at 25 one end only. Between the sides 51, 52 of the work presser foot 5 I dispose the label presser foot 6 carried on a spring pressed presser foot bar 37 which is disposed in the sewing machine head 3 as is usual for presser foot bars.

30 The presser foot bar is provided with a cross bar 371 secured thereto by screw 372 through bracket 373 as seen particularly in Fig. 14, the bracket being, in effect, a spacer block as here shown. The cross bar 371 is moved rigidly up and 35 down with the bar 37.

The label presser foot 6 is provided with a transverse slide groove 61 which embraces the lower edge of the cross bar 371 and is adapted to reciprocate on that slide bar. The bar 371 is longitudinally slotted at 371' and a cross pin 62 engages the slot and holds the presser foot 6 in operative relation to the cross bar 371 and limits its movement thereon.

The label presser foot 6 is embraced by the side arms 51, 52 of the work holder foot and the work holder foot is adapted to reciprocate back and forth in engagement with the said label presser foot. The label presser foot is made perfectly smooth like a flatiron on its under surface where 50 it contacts with the label and it is provided with a main part 63 and an auxiliary cooperating forward part 64 which are connected together by a bracket arm 65, the space between these parts forming a stitching slot for the passage of the 55 label presser foot along the sewing machine needle, so that a label beneath will be held down by the presser foot, both in the front and the rear of the sewing machine needle in operation. This slot is, in practice, about $\frac{1}{16}$ of an inch wide.

60 The under side of the presser foot is provided with longitudinal grooves 66 extending from front to rear through both the parts 63 and 64. These are to accommodate the pair of label guides 39, 39 which are adjustably secured by set screws 65 391 to the inner sides of the side members 51, 52 of the presser foot. These guides are capable of adjustment back and forth to vary the label space in the work presser foot. The grooves 66 also accommodate the label stops 40 which are 70 alined with the guides 39 and are of such length that they project through the auxiliary part 64 of the presser foot into proximity with its forward edge.

The under sides of the stops 40 and the forward 75 ends of the guides 39 are serrated so that they en-

gage the fabric 34 securely. The label 41 is delivered down over the guides 39 by the feed pusher 42. (It may be done with the fingers.) This pusher is secured to cross bar 421 provided with a stop finger 422. The feed label pusher is held in withdrawn position by spring 423 which is connected to the forwardly projecting finger 424 as seen in Fig. 1.

By adjusting the label slides 39, space can be left for a label of any length desired. By adjusting the side bars 51, 52 the width of the label accommodated can be regulated and, of course, for each label within limits the machine can be adjusted by adjusting the throw of the feed segments. If there is a material difference in size 15 new cams on wheel 19 will need to be substituted.

The needle bar and needle are of usual construction and my improved label presser foot is adjusted in relation thereto as indicated particularly in Fig. 5 in its initial position. The label 20 presser foot reciprocates from side to side so that the slot therein travels laterally from side to side in its relation to the needle. When the sides of the label are being stitched, the label presser foot stands still and the work presser foot reciprocates therebeneath in a forward and backward movement carrying the work under the label presser foot.

When other designs than a rectangle are being 25 stitched, the label presser foot may be reciprocated from side to side at the same time that the work presser foot is reciprocating forward and back.

The label presser foot, as pointed out, is carried by the presser foot bar 37. This bar has a 35 laterally projecting pin 374 at the top by means of which it is actuated. This is done by the slide 33 which has outwardly projecting pin 381 engaged by the slot 382 in the forward end of the lever 383. This lever 383 is fulcrumed at 384 40 and is connected by link 385 to the rear end of the lifting lever 35. Owing to the position of the fulcrum 384 the long end of the lever 383 raises the slide 38 at a more rapid rate than the lifting 45 of the work presser foot, so that the label presser foot is elevated above the work presser foot when the presser feet are raised.

Thus the simple matter of raising the presser foot for the insertion of the fabric of a garment elevates the label presser foot to permit the introduction of a label. These levers are so timed that the label presser foot is raised first and, of course, can be kept in elevated position after the work holder foot has grasped the fabric to permit the introduction of the label under the 50 label presser foot, when the presser foot can be entirely released and the label can be clamped upon the previously clamped fabric of the garment.

I provide my improved presser foot means with 55 a special top thread cut-off and clamp. This consists of reciprocating knife 43 having a beveled end 431 with a right-angle notched cutting edge 432, and a lower cutter 433. A spring 434 having screw 435 holds the knife 43 yieldingly 60 against the bar 433. The knife is held in withdrawn position by spring 44 carried on screw 441, as seen in Fig. 16.

The knife is operated from rockshaft 45 by rockshaft arm 451, the end of which projects 70 through a slot 434 in the rear end of said knife 43. Rockshaft 45 is operated by compound lever mechanism consisting of arm 452 on the end of which is fulcrumed lever 453 the short end of which is connected to the elevating chain 46, see 75

Fig. 13. The rear end of this auxiliary lever contacts with the upper surface of the presser shoe 5, thus making a compound lever movement of high power to insure the operation of 5 the knife against the comparatively heavy spring.

This knife operating chain is operated by the vertically reciprocating slide 47 which is notched at 471 for engagement by the dog 48 carried by 10 presser foot actuating slide 38 pivoted at 481 on the said slide. The dog is provided with a stop pin 482 which projects forwardly through a slot 491 in the cover plate 49. This slot 491 is formed with a cam projection 492 which engages the pin 15 482 and withdraws the dog 48 from engagement with notch 471, thus releasing the slide 47 and permitting the knife to be withdrawn by the action of the spring 44.

Pivoted at the side of the head 3 is the guide 20 50 pivoted at 501 on the front side of the cover plate 49. This guide is controlled by cam lever 502 on pivot 503 on the feed cover plate 49, the guide bar being supported by the bracket 504 secured by the same pivot as the lever 502. 25 When the lever 502 is operated and cams the guide 50 over to the right, as seen in Fig. 17, the straight edge of the same engages the pin 482 carrying the same straight up and preventing engagement of the notch 471 by the dog 48, 30 so that by adjusting lever 502 it is possible to raise the presser foot and manipulate the same indefinitely without any action whatsoever on the cut-off knife which depends for its action on the engagement of the dog 48 with the notch 471 in slide 47.

The bottom knife and thread holder are not described herein as they are of usual construction and are not here detailed or illustrated.

I have now described the various parts of my 40 machine and I will now indicate their operation by describing an evolution of the machine in the attachment of a label and what the different parts do in that behalf.

In the beginning the presser foot structure is 45 elevated to the maximum by a down pull on the bar 33 by the chain or other means attached thereto. This reacts through link 331 on the arm 29' to actuate rockshaft 29. The operation of 50 the rockshaft 29 actuates the cam finger 291 pulling down the slide 292, thereby through the actuating pins 294, 295 operating the levers 262 and 282 to release the pawls 26 and the detents 28.

By continued operation pin 291' on arm 291 55 strikes the stop notch 195 on the cam wheel 19, setting the same back a plurality of steps. The pressure on bar 33 is then sufficiently released to allow the work presser foot to engage the garment fabric inserted therebeneath. When this 60 is engaged the label presser foot is still in elevated position and a label is placed on the label guides 39 and fed to place by manipulation of the pusher 42.

The label being thus in position the bar 33 is 65 completely released and the label is clamped against the fabric, and the fabric securely clamped against the apertured work plate beneath.

The sewing machine is then started by a pull 70 on the starting chain, which permits a complete evolution, stitching a label in place. The needle descends two or three stitches in advance of the stopping position and the segment gear 11 feeds the presser foot, carrying with it the label in the work presser foot, forwardly underneath the

label presser foot while the upper left hand portion, as illustrated in Fig. 5 is being stitched.

Then the cam for the segment 11 comes to rest and the cam for actuating the segment 15 is thrown into operation and advances the label, work holder presser foot, and label presser foot toward the left as illustrated in Figs. 4 and 5, stitching the rear edge of the label.

When the rear edge is completed the cam at that side comes to rest and the cam for controlling the segment 11 is thrown into work, reversing the movement thereof and carrying the label and work holder under the label presser foot to the rear, stitching the right hand end of the label, as seen in Fig. 5, until the corner is reached, when that cam comes to rest and the segment 15 is actuated, carrying the whole structure to the right and stitching the front end of the label up to the left-hand lower corner, see Fig. 5.

Then the direction again changes by means of 20 segment 11 and the work holder slides the label and work under the label presser foot, completing the stitching and overlapping the last two or three stitches at the point of beginning.

When the stitching is completed the presser foot is raised by a pull on the bar 33 which actuates lever 35 and this, through the link connection 335, operates the presser foot, raising lever 33 which operates on the label presser foot, raising slide 38 to elevate the same.

With the structure as set in Fig. 2, the elevation of the slide 38 elevates the dog 48 which engages in notch 471 in the side of the slide bar 47. This controls the cut-off knife, forcing the knife outward past the thread, hooking the same so that 35 when the pin 482 passes up on the cam 492 the same will be tripped, the thread will be severed and the end will be clamped between the spring 434 and the knife 43, as seen in Fig. 12. The garment with the attached label can then be removed, completing the evolution.

I desire to state that my structure can be greatly varied in its details without departing from my invention. I have shown the label presser foot rectangular in form, but as pointed out its form can be varied, its dimensions can be varied, and the label presser foot can be conformed to an aperture in the work presser foot and the cams organized to guide the work in proper relation to the needle.

I have shown various adjustments, all of 50 which can be omitted when it is desired to use the machine for standard size, of which a large quantity is to be produced.

The actuating means for the work holder is 55 available for various styles and kinds of work holder and presser shoes and while the details of one are especially adapted to the other, they may be used in other relations. So, also, the particular work holder, work presser foot and label presser foot can be made use of with the means for driving and controlling such work holder and presser foot devices as appears in my Patent No. 1,223,617, April 24, 1917.

The stitching of labels and patches for reinforcement on garments is, of course, a very important service to be rendered by my machine. However, it is frequently desirable merely to stitch forms such as rectangles and squares in portions of a garment or fabric for reinforcing 70 or for various purposes.

I desire to claim my invention for that purpose as well as for the purpose of attaching labels and patches. By the proper construction and relation of parts it would also be possible to stitch 75

a name or symbol on to the garment or fabric directly and label it in that way, which, of course, would be an important service for my improved machine.

5 I also desire to state that in the operation of this machine where labels are applied to heavy or stiff fabric, or to leather and other material of considerable integrity, the bottom work supporting plate can be dispensed with and the work 10 presser foot can be made use of to force the work against the smooth needle plate, when the whole will be manipulated and very effective work done. This would be wholly impossible with light flexible fabrics where it is desirable and necessary to stretch the same across the apertured work holder plate in order to make the same 15 effective.

Having thus described my invention what I claim as new and desire to secure by Letters 20 Patent is:

1. In a machine of the class described, the combination of an apertured work holder plate, a work presser foot with adjustable side members to correspond to the aperture in the work plate, 25 an arm for raising said work presser foot, a carrier for said work holder plate, label guides within the space between said side members for guiding a label to the work held by the work holder, a label presser foot slotted to accommodate said guides and adapted to the reciprocation of the work holder in relation thereto, a presser foot bar for carrying the said label presser foot having a cross arm at its lower end on which the said label presser foot can reciprocate, and 30 elevating means for the said label presser foot bar comprising a lever having a longer lever arm than the arm for raising the work presser foot and coupled thereto, whereby the label presser foot and the work presser foot are raised successively.

2. In a machine of the class described, the combination of a work presser foot with adjustable side members, an arm for raising the same, a work holder plate, a carrier for said work holder plate, label guides within the space between said side members for guiding a label to the work held by the work holder, a label presser foot slotted to accommodate said guides and adapted to the reciprocation of the work holder in relation thereto, a presser foot bar for carrying the said label presser foot having a cross arm at its lower end on which the said label presser foot can reciprocate, and elevating means for the said label presser foot bar comprising a lever having a longer lever arm than the arm for raising the work presser foot and coupled thereto, whereby the label presser foot and the work presser foot are raised successively.

3. In a machine of the class described, the combination of a work holder having a carrier plate, a work presser foot with adjustable side members, a carrier for said work holder, label guides within the space between said side members for delivering a label to the work held by the work holder, a label presser foot slotted to accommodate said guides and adapted to the reciprocation of the work holder in relation thereto, a presser foot bar for carrying the said label presser foot having a cross arm at its lower end on which the said label presser foot can reciprocate, and elevating means for the said label presser foot bar.

4. In a machine of the class described, an apertured work plate, a work presser foot with elongated opening therein, a label presser foot with presser foot bar for maintaining the same

in proper relation to the needle of the sewing machine, guide means for guiding the label presser foot laterally in its relation to the said needle, and slot means for permitting the movement of the said work presser foot and the movement of work under the label foot at right angles to the movement of said label presser foot.

5. In a machine of the class described, a work presser foot with elongated opening therein, a label presser foot with presser foot bar for maintaining the same in proper relation to the needle of the sewing machine, guide means for guiding the label presser foot laterally in its relation to the said needle, and slot means for permitting the movement of the said work presser foot and the movement of work under the label foot at right angles to the movement of said label presser foot.

6. In a machine of the class described, the combination of a work holder means having a step by step feed, a ratchet wheel for actuating the same provided with actuating and detent pawls, a connection between the said pawls, a rock lever with a cam for actuating the said connection to withdraw the said pawls from engagement with the ratchet wheel, and a stop means cooperating therewith to set back the ratchet wheel.

7. In a machine of the class described, the combination of a work holder plate for carrying the work in a predetermined path, a work holder carrier plate for said work holder having racks with elongated rack teeth at right angles to each other thereon to slide on actuating pinion segments, actuating pinion segments engaging said rack teeth in sliding engagement therewith, and cams for actuating the said pinion segments having alternate rest and actuating surfaces to operate successively so that the said pinion segments will operate successively to advance the movement of the work and reverse the same for the application of a label or the like.

8. In a machine of the class described, the combination of a work holder plate for carrying the work in a predetermined path, a work holder carrier plate for said work holder having racks with elongated rack teeth at right angles to each other thereon to slide on the actuating pinion segments, pinion segments engaging said rack teeth in sliding engagement therewith, and cams for actuating the said pinion segments having alternate rest and actuating surfaces to operate successively so that the pinion segments will operate successively to advance the work.

9. In a machine of the class described, the combination with a work holder adapted to travel forwardly and backwardly and laterally, control means therefor with intermittent actuating means, of a double-faced cam with alternate rest and actuating surfaces to operate successively for the movement of said work holder forwardly, backwardly and laterally.

10. In a machine of the class described having work holder means, the combination of a double faced cam for actuating the work holder means, said cam having ratchet teeth on its periphery, a ratchet for actuating said cam, detents for holding the same, a stop motion device, and means adapted to coact with the stop motion device to release the said ratchet, and means to set back the ratchet of said cam to insure overlapping of the stitching at the beginning and end of the work.

11. A label presser foot with smooth bearing surface on its under side to permit relative sliding movement of the said presser foot and label

and having a transverse slot to permit the passage of the same across the stitching point of the needle to permit a label or work to be carried under the needle and to be held at both 5 sides of the stitching line, and means to shift said presser foot in relation to said needle.

12. A label presser foot with smooth bearing surface on its under side to permit relative sliding movement of the said presser foot and label 10 and having a transverse slot to permit the passage of the same across the stitching point of the needle, and means to shift said presser foot in relation to said needle.

13. In a machine of the class described, the 15 combination of a work holder plate for carrying the work in a predetermined path, a work holder carrier plate for said work holder having racks with elongated rack teeth at right angles to each other thereon to slide on the actuating pinion 20 segments, pinion segments engaging said rack teeth in sliding engagement therewith, a sleeve supporting one of said pinion segments for rotation, a driving shaft through said sleeve, a driven shaft driven thereby at right angles to said driving 25 shaft and supporting said other pinion segment for rotation, a double faced cam, a cam follower for each face of said cam, means connecting one cam follower to said pinion segment supporting means to rotate the same and its pinion segment, and means connecting the other cam follower to said driving shaft to rotate said 30 shaft and said driven shaft and the other pinion segment, each of said cam faces having alternate rest and actuating surfaces so disposed

disposed that an actuating surface of one cam face is operating while a rest surface of the other cam face is functioning, so that the pinion segments will operate successively to advance the work.

14. In a machine of the class described, the combination of a work holder plate for carrying the work in a predetermined path, a work holder carrier plate for said work holder having racks with elongated rack teeth at right angles to each other thereon to slide on the actuating pinion segments, pinion segments engaging said rack teeth in sliding engagement therewith, pinion segment means supporting one of said pinion segments for rotation, a driving shaft disposed parallel with the axis of said pinion segment supporting means, a driven shaft adapted to be driven by said driving shaft and at right angles thereto and supporting said other pinion segment for rotation, a double faced cam, a cam follower for each face of said cam, means connecting one cam follower to said pinion segment supporting means to rotate the same and its pinion segment, and means connecting the other cam follower to said driving shaft to rotate said shaft and said driven shaft and the other pinion segment, each of said cam faces having alternate rest and actuating surfaces so disposed that an actuating surface of one cam face is operating while a rest surface of the other cam face is functioning, so that the pinion segments will operate successively to advance the work.

ARTHUR ROSENTHAL.
